VALVE GUIDE SCRAPER RING

Robert F. Huddleston, Indianapolis, Ind., assignor to P. R. Mallory & Co., Inc., Indianapolis, Ind., a corporation of Delaware

Application May 8, 1943, Serial No. 486,179

4 Claims. (Cl. 123—188)

This invention relates to engine valve guides. An object of the invention is to improve valve guides and valve guide scraper rings and their method of mounting.

Other objects of the invention will be apparent from the description and claims.

In the drawing:

Figure 1 is a section through a valve assembly illustrating the mounting of a valve guide and scraper ring;

Figure 2 is a section on the line 2—2 of Figure 1;

Figure 3 is a perspective view of a valve guide scraper ring; and

Figure 4 is a perspective view of the valve guide for holding the scraper ring.

In the operation of internal combustion engines such as airplane engines under some conditions carbon deposits are built up on the valve stems causing rapid wear and damage to the valve guides and valve stem. It is desirable therefore to provide a means for removing the carbon from the portion of the valve stem which enters the valve guide. An ordinary steel guide or guide made of other commonly used metals, however, is not of sufficient hardness and abrasion resistance to scrape off the carbon over extended periods of operation. According to the present invention the valve guide is provided with a scraper ring of hard refractory metal composition, the scraper ring being secured to the valve guide by interlocking portions.

Referring to the drawing the valve assembly shown in Figure 1 comprises a valve 10 seated in a valve seat 11 in the engine block 12. Valve 10 has a stem portion 13 which slides in a valve guide 14 secured in the engine block or cylinder head. Guide 14 carries at its end nearest the head of the valve the scraper ring 15 formed of a hard refractory metal composition.

The valve guide 14 is illustrated in Figure 4 and the scraper ring 15 in Figure 3.

Valve guide scraper ring 15 is produced by powder metallurgy methods of mixtures of refractory metal powders with bonding metals. The preferred composition and method of manufacture is as follows: The final composition ranges from 55% to 65% molybdenum, 45% to 35% silver. Small percentages of copper, cobalt, nickel, iron, manganese, and carbon may be present. While several methods may be used in the manufacture of valve guide scraper rings, I prefer to mix molybdenum powder with a small percentage of silver powder, press, sinter at a suffi-

ciently high temperature to cause bonding of the refractory molybdenum particles and subsequently impregnate with additional silver at a temperature above the melting point of silver so as to form a strong, homogeneous, dense product having high physical properties coupled with good electrical and thermal conductivity. I do not wish, however, to be limited to this method of manufacture. Other methods which have 10 proven successful have been:

a. Mix all of the powders together, press and sinter at a temperature below the melting point of either the molybdenum or silver.

b. Mix all of the powders together, press and sinter at a temperature above the melting point of silver but below the melting point of molybdenum.

c. Press molybdenum powder to a suitable density, sinter at a sufficiently high temperature to 20 cause bonding of the molybdenum particles and incorporate all of the silver by impregnating at a temperature above the melting point of silver.

Other refractory metal compositions which can be used are:

25 50% to 80% tungsten, balance silver
40% to 70% tungsten carbide, balance silver
30% to 70% molybdenum carbide, balance silver
25% to 50% titanium carbide, balance silver
30 40% to 70% tantalum carbide, balance silver.

Small percentages of copper, cobalt, nickel, iron or manganese may also be present. Various percentages of the refractory elements or carbides may be mixed with each other.

35 35 These compositions may be prepared in a manner similar to that used to fabricate the preferred composition.

The scraper ring is preferably molded in a die to substantially the final shape and dimensions 40 required and then a finish machining operation is applied after sintering and alloying. As illustrated in Figures 1 and 3 the scraper ring has a central cylindrical opening 16 passing therethrough. The scraping face 17 is formed on the larger diameter end 21 of the ring with a conical surface to give a satisfactory cutting edge and carry carbon particles away from the valve stem. The smaller end of the scraper ring is provided 45 with a conical tapered portion 18 to aid in assembly, this tapered portion merging with an annular ridge 19, a short distance back from the smaller end of the ring. An annular groove 20 is provided between ridge 19 and the larger end 21 50 of the ring.

Valve guide 14 is formed of a tubular piece of metal and is adapted to receive scraper ring 15 by machining a pair of annular grooves 22 and 23 on its inside surface near one end. The grooved portion is also slotted with six equally spaced longitudinal slots 24 to divide the end of the guide into six legs 26. The other end of the guide is provided with an enlarged portion 25.

The parts are assembled by inserting the tapered smaller end 18 of the scraper ring in the slotted end of guide 14 and applying sufficient pressure to spread the six legs to permit flange 19 to enter annular groove 22 inside valve guide 14. When the flange 19 is thus snapped into the groove, the six legs of the valve guide will return to substantially their original position thus effectively locking the scraper ring in the end of the guide. The scraper ring at this time is free to rotate within the guide. Annular groove 23 in the guide member permits sufficient flexibility of the six legs to permit assembly as above described.

The valve guide and scraper ring assembly is then inserted in the aperture in the engine block or cylinder head provided for it. This aperture tightly engages the outer surface of valve guide 14 firmly pressing the six legs 26 against the scraper ring to prevent any relative motion after final assembly.

By this method of assembly no welding or brazing is required between the valve guide and the scraper ring. Moreover it is frequently necessary or desirable to replace the scraper rings during service. The present invention makes this operation very simple, it merely being necessary to withdraw the valve guide, remove the worn scraper ring and snap in a new ring.

While specific embodiments of the invention have been described, it is intended to cover the invention broadly within the spirit and scope of the appended claims.

What is claimed is:

1. A valve guide assembly comprising a tubular metal guide having an internal annular groove 45

near one of its ends and a plurality of longitudinal slots extending back from said end to divide the grooved portion into a plurality of individual resilient legs, and a scraper ring having an external annular flange received in said internal annular groove whereby said guide and ring are locked together.

2. A valve guide assembly comprising a tubular metal guide having an internal annular groove 10 near one of its ends and a plurality of longitudinal slots extending back from said end to divide the grooved portion into a plurality of individual resilient legs, and a scraper ring having an external annular flange received in said internal annular groove whereby said guide and ring are locked together, one of said parts having a tapered conical face at its end to produce spreading of said legs.

3. A valve guide assembly comprising a tubular metal guide having an internal annular groove 20 near one of its ends separated from said end by an internal flange and a plurality of longitudinal slots extending back from said end to divide the grooved portion into a plurality of individual 25 resilient legs, and a scraper ring of hard refractory metal having an external flange received in said internal annular groove whereby said guide and ring are locked together.

4. A valve guide assembly comprising a tubular metal guide having an internal annular groove 30 near one of its ends separated from said end by an internal flange and a plurality of longitudinal slots extending back from said end to divide the grooved portion into a plurality of individual 35 resilient legs, and a scraper ring of hard refractory metal having an external flange received in said internal annular groove whereby said guide and ring are locked together, said scraper ring having a conical surface flaring outward from one of its ends and merging with said external flange to produce spreading of said guide legs during assembly.
